(57) **CLAIM**

The ornamental design for a set of balancing steps, as shown and described.

DESCRIPTION

FIG. 1 is a perspective view of a set of balancing steps, showing my new design;

FIG. 2 is a front view thereof;

FIG. 3 is a right view thereof;

FIG. 4 is a left view thereof;

FIG. 5 is a back view thereof;

FIG. 6 is a bottom view thereof;

FIG. 7 is a top view thereof;

FIG. 8 is an enlarged view of the encircled area 8 of FIG. 3; and,

FIG. 9 is an enlarged view of the encircled area 9 of FIG. 7. The broken lines on the drawings depict portions of the set of balancing steps that form no part of the claimed design. The dot-dash lines depict the enlarged view boundaries that do not form part of the claimed design.
